UNITED STATES PATENT OFFICE.

GEORGE WALTER, OF SHELBY TOWNSHIP, RIPLEY COUNTY, INDIANA.

WILLOW-BARK REMOVER.

1,310,223.

Specification of Letters Patent. Patented July 15, 1919.

Application filed April 12, 1918. Serial No. 228,172.

To all whom it may concern:

Be it known that I, GEORGE WALTER, a citizen of the United States, residing in Shelby township, in the county of Ripley and State of Indiana, have invented a new and useful Willow-Bark Remover, of which the following is a specification, reference being had to the accompanying drawings and to the letters and figures of reference 10 marked thereon.

This invention relates to a machine for removing the bark from the elongated pendulous branches of willow trees in order to prepare the willow wood as required for 15 use in the making of various articles, willow baskets, for instance, and many other articles; the invention having reference more particularly to a machine that is adapted for use in the localities where the 20 willows grow and to expeditiously remove the willow bark while green and naturally in the desired condition for the removal of the bark.

An object of the invention is to provide 25 an osier peeler or machine whereby willow branches may be prepared for use at the minimum cost and the least expenditure of labor. Another object of the invention is to provide means whereby the shipper of willow branches may be enabled to advantageously ship and dispose of the branches, and particularly to obviate steaming and removing the willow bark after having become dry. A further object is to provide a 30 bark-removing machine that shall be so constructed as to have great capacity and adapted to be attended and economically operated by an unskilled attendant or a small 35 number of attendants. A still further object is to provide a machine whereby the bark may be removed from the flexible wood of the willow branches without injuring the wood.

With the above-mentioned and other objects in view, the invention consists in a machine having stripper heads adapted to loosen and strip the willow bark from the willow branches when the branches are drawn between the heads, movably supported carriers adapted to carry the branches into contact with the stripper heads, and means whereby to guide the branches to the carriers, the machine preferably having also means for beating and 55 removing particles of the bark that may adhere to the wood after having been loos-

ened by the stripper heads. The invention consists also further in the novel devices, and the parts and combinations and arrangements of parts, as hereinafter particularly described and further defined in the accompanying claims.

Referring to the drawings,—Figure 1 is a side elevation of a machine constructed substantially in accordance with the invention; 60 Fig. 2 is a top plan of the machine of which duplicate mechanisms thereof are omitted; Fig. 3 is a perspective view of one of the beater devices of the machine; Fig. 4 is a section approximately on the line IV—IV 65 on Fig. 2; Fig. 5 is a rear end elevation of the machine partially broken away to omit duplicate mechanisms thereof; Fig. 6 is a fragmentary vertical section showing the stripper devices and means for cleaning 70 them; Fig. 7 is a fragmentary sectional detail reproducing portions of Fig. 6 on an enlarged scale with parts thereof in relatively different positions; Fig. 8 is a fragmentary sectional elevation of the head portion of the machine; Fig. 9 is a fragmentary detail of the device for cleaning the stripper devices; Fig. 10 is a section on the line X—X on Fig. 9; Fig. 11 is a fragmentary 75 transverse sectional elevation of the head portion of the machine; Fig. 12 is an enlarged detail of the devices for carrying the willow branches to the stripper heads to be operated upon; Fig. 13 is a fragmentary section on the line XIII—XIII on Fig. 4; 80 Fig. 14 is a plan of the carrier for the willow branches; and, Fig. 15 is a perspective 85 view of one of the cleaner blades comprised in the beater apparatus.

Similar reference characters in the different figures of the drawings indicate corresponding elements or features herein referred to.

As preferably constructed the bark-removing machine comprises a frame which 95 may be of any desired or convenient length and width to accommodate multiple mechanisms or a plurality of sets of devices which may be fed by one attendant. To this end the frame comprises suitable end portions 100 1 and 2 to which side portions or rails 3 and 4 are connected and extending forward beyond the end portion 1, the forward portions of the rails having standards 5, 5' 105 thereon. The frame comprises also suitable transverse members 6, 7, 8, 9, and a longitudinal side rail 10 connected with the lower 110

portions of the end portions 1 and 2 of the frame.

A driving shaft 11 is rotatably mounted upon the side rails 3 and 4 adjacent to the 5 forward end portion 1 of the frame and has a suitable pulley or wheel 12 thereon whereby to drive the shaft. A driving sprocket wheel 13 is mounted on the shaft 11 and as 10 preferably arranged is rotatable on the shaft and adapted on one side to have frictional contact with a clutch plate 14 that is secured to the shaft, the opposite side of the wheel being adapted to have frictional contact with a friction clutch disk or plate 15 15 which is splined on the shaft. A collar 16 is secured to the shaft and a coil spring 17 is arranged on the shaft between the collar and the hub of the clutch disk, whereby the wheel 13 is clutched to the shaft 11 but permitting it to be disconnected from the shaft when desired. A cross-bar 18 is supported by the frame and has a suitable pivot 19 to which a shifting-lever 20 is connected between its ends, the shifting-lever having a 25 suitable shifting fork on one end that is operatively connected with the hub of the clutch disk 15, a connecting rod 21 being pivoted to the opposite end portion of the shifting-lever. A controlling lever 22 is pivotally mounted on the frame of the machine and is connected to the connecting rod 21. The lever 22 is provided with a latch 23 to engage a notched quadrant 24 mounted on the frame, so that the clutch disk 15 may be 30 manually controlled.

At the rear end of the frame a shaft 25 is mounted above the member 6 and a shaft 26 is mounted below the member 6, the shafts having guiding sprocket wheels 27 and 28 40 thereon respectively, to be rotated either on or with the shafts as may be preferred, to arrange them. Preferably the shafts are steadied by means of a yoke 29 secured to the member 6 and having arms 30 and 31 45 suitably adapted to support the shafts respectively.

An endless belt 32 is arranged on the driving wheel 13 and the guide wheels 27 and 28, the belt being of the sprocket chain type. 50 A suitable number of shafts 33 are mounted upon the rails 3 and 4 and preferably steadied by means of yokes 29' and having suitable arms as above-mentioned for supporting the shafts which have sprocket 55 wheels 34 thereon to support and guide the upper portion of the belt 32 and prevent sagging of the belt. A suitable number of shafts 35 are mounted below the frame rails 3 and 4 and support sprocket wheels 36 in 60 contact with the lower or return portion of the belt. One carrier belt and its driving and guiding wheels are described as being sufficient to illustrate a gang or plurality of carrier belts which in practice are mounted 65 on one frame.

The carrier belt is provided with a suitable number of grippers for carrying the branches of the willow trees, the grippers comprising base clamps 37, 37' respectively having each a stationary jaw 38 and a guide 70 arm 39 thereon, and having also a guide ear 40 and a pivot 41 connected with the ear. A jaw 42 is movably connected with the base clamp and in respect to the jaw 38 by means of the pivot 41 and has a controlling arm 43 75 preferably provided with a roller 44. A spring 45 is arranged under compression between the arms 39 and 43 to force the jaw 42 toward the jaw 38.

For the purpose of enabling the attendant 80 to feed the willow branches to the grippers a feed-plate 46 is suitably mounted on the standards 5 and 5' at a suitable inclination to direct the willow branches downward toward the driving wheel 13, the top of the 85 feed-plate being provided with two oppositely arranged guides 47 and 48 to guide the branches laterally. A stop gate 49 is arranged near the lower end of the feed-plate to control the delivery of the willow 90 branches to the grippers. The stop gate is suitably supported to swing away to release the branches and preferably is secured to a hinge rod 50 suitably supported rotatably and having a controlling arm 51 thereon to 95 which a suitably supported retracting spring 52 is connected, the stop gate being normally horizontal to be pushed upward by means of the gripper jaws. A curved 100 guide plate 53 is mounted on the member 18 to be engaged by the roller 44 so as to move the jaw 42 to open position at the proper time to receive the willow branch and carry it away from the feed-plate, the spring 45 acting to close the gripper jaw when the 105 roller has passed the guide plate 53. Another guide plate 54 is mounted also on the member 18 to be engaged by the arm 39 to prevent the belt 32 and the gripper jaws from being swayed when the arm 43 is forced 110 by the plate 53 against the spring 45.

A low platform 55 is connected to the rear end portion of the machine frame and supports two stems 56 and 57 at a suitable distance from the rear end of the frame, the 115 stems being the supporting portion of wooden stripper heads 58 and 59 oppositely arranged and secured to the stems respectively, the adjacent upper portions of the heads being curved to guide the willow 120 branches downward between the heads. The stems are composed of flat bar metal to permit slight elasticity, so that the heads can be forced slightly apart by the passing willow. The adjacent faces of the heads are 125 provided respectively with metallic strips 60 and 61 which have rounded faces to cause the willow bark to be loosened and stripped from the wood without scraping or cutting the wood. A post 62 is secured to the plat- 130

form 55, and a tension bar 63 is connected thereto and also with the stripper heads 57 to yieldingly hold the head to the opposite head 56, the tension bar being preferably 5 composed of wood and sufficiently thin to be slightly elastic. Another post 64 is secured also to the platform 55 and supports a controlling spring 65 in contact with the bar 63.

Provision is made for retaining the willow 10 branches between the stripper heads during operations, and provision is also made for clearing the stripper heads of gummy substance produced by the willow sap and particles of the bark which would tend to clog 15 and impair the efficiency of the heads; and, to this end a movable guide is provided to retain the willow and permit free operation of the cleaner device. Therefore one of the 20 stripper heads is provided with an axle stud 66 on which a star-wheel is rotatably mounted and having preferably four radial arms 67, so that one arm may normally extend horizontally across the path of the willow branch as it is drawn downward between 25 the stripper heads. The arm is supported against downward movement by means of a latch bolt 68 mounted in the head 59 and normally projected under the arm by means of a spring 69 arranged in the head. The 30 head suitably supports a pivot 70 on which a trigger 71 is mounted that is connected to the latch bolt for retracting the latter. Thus the grippers may place the willow branches between the stripper heads and 35 draw the branches downward and against the arm 67 to remove the bark, after which the grippers carry the stripped branches toward the forward end of the machine. The machine frame has a cross-bar 72 on which a 40 curved guide plate 73 is mounted to be engaged by the roller 44 to move the arm 43' so as to cause the willow branch to be released from the gripper jaws, a guide plate 74 being mounted also on the cross-bar 72 to be engaged by the arm 39' to prevent lateral deflection of the carrying belt 32 and insure proper action of the gripper jaws to drop the branches on to the ground or floor beneath the machine.

45 The carrier belt 32 carries a cleaner, or preferably a cleaner in advance of each set of grippers, and each cleaner preferably comprises a base clamp 75 which is secured to the belt 32 and has a pivot 76 thereon whereby a finger base 77 is connected to the base clamp. The base has a finger 78 thereon adapted to be carried between the stripper heads to clear the debris therefrom, and it has also a trip finger 79 to engage the trigger 50 71 for retracting the latch bolt 68 to permit the finger 78 to move the guide arm 67 downward out of the path of the finger. The finger base 77 is maintained in normal position by means of a spring 80 suitably 55 arranged in contact with the base and in

contact with a portion of the base clamp 75, a portion of the finger base being normally held by a spring against a stop 81 on the base clamp. For the purpose of swinging the finger 78 around so as to clear the stop 70 gate 49, a curved guide 82 is mounted on the feed-plate 46 and adapted to guide the finger 78 around past the end of the stop gate 49 as the cleaner device is carried upward over the sprocket wheel 13. 75

The frame of the machine has a stand 83 on one side thereof which supports a suitable housing 84, which preferably is box-shaped and the top thereof is constructed as a grating 85. A plurality of shafts 86 and 87 are 80 rotatably mounted in the housing below the grating and are provided with radially arranged fingers 88 and 88' respectively that are adapted to be moved through the openings in the grating. A sprocket wheel 89 is 85 secured to the shaft 86 and is in connection with a sprocket chain 90 that is connected with a sprocket wheel 91 secured to the shaft 11. A sprocket wheel 92 is secured also to the shaft 86, a sprocket wheel 93 is secured 90 to the shaft 87, and a sprocket chain 94 is connected with the sprocket wheels 92 and 93. Two knife-bars 95 and 96 are suitably supported in the housing 84 and support a suitable number of cleaning knives 97 and 98 95 for cleaning the fingers of one of the shafts, and similar knives 97' and 98' for cleaning the fingers of the remaining one of the shafts.

The reference numerals 99, 99' indicate the 100 willow branches carried by the grippers of the machine.

In practical use the branches of the willow tree are placed one at a time upon the feed-plate 46 with the thicker end of the branch 105 against the stop gate 49, and as the shaft 11 is driven the carrying belt 32 is moved in the direction indicated by the darts adjacent thereto, with the result that the grippers are brought from below and upward over the 110 driving wheel 13, the grippers being properly opened as above described, and being brought into contact with the gate 49 pushes it upward and permits the willow branch to be received between the gripper jaws 115 which become automatically closed and carry the branch rearward to the stripper heads where they are drawn through between the heads which loosen and strip the bark from the wood, the branches being carried forward until automatically dropped from the grippers. The branches are gathered up in bunches and placed by hand upon the grating 85 so as to be approximately parallel with respect to the shafts 86 and 87, 120 in which arrangement the fingers of the shafts beat the branches while the latter are shifted about on the grating with the result that particles of loosened bark which may adhere to the wood are removed, leaving the 125 130

branches in proper condition for shipment or use.

Having thus described the invention, what is claimed as new is—

- 5 1. A willow bark remover including a pair of stripper heads, a separate feed-guide provided with a movable stop gate, a carrier belt to operate between the feed-guide and the stripper heads, and grippers mounted on the carrier belt to be carried past the feed-guide and to engage and move the stop gate from normal position.
- 10 2. A willow bark remover including co-operating stripper heads, controllable movable means for gripping and carrying the willow to and between the stripper heads, controllable guiding devices controlled by the movable means to deliver and to guide the willow to the movable means, means for controlling the movable means to receive the willow, and means for controlling the movable means to release the willow.
- 15 3. A willow bark remover including a frame, a feed-guide provided with a movable stop gate at one end portion of the frame, stripper devices at the opposite end portion of the frame, an endless belt to operate on the frame between the feed-guide and the stripper devices, grippers carried by the belt past the stripper devices and adapted to engage and move the stop gate from normal position, and a cleaner device mounted on the belt to be carried thereby into contact with the stripper devices.
- 20 4. In a willow bark remover, the combination of stripping apparatus comprising two uprightly-supported stripper heads, one of the heads being yieldingly forced toward the other, a guide arm supported horizontally by one and extending approximately to the other of the stripper heads, and an endless carrier belt to operate adjacent to the stripper heads, with a device carried by the belt adapted to carry the willow between the stripper heads and across the guide arm.
- 25 5. In a willow bark remover, the combination with a driving wheel and two guide wheels arranged one below the other, of a carrier belt extending about said wheels to be driven by the driving wheel, a pair of co-operating stripper heads supported adjacent to the guide wheels, a gripper device mounted on the carrier belt to carry the willow to the stripper heads, and a cleaner comprising a finger having a base secured to the carrier belt to enable the belt to carry the finger between the stripper heads.
- 30 6. In a willow bark remover, the combination with a driving wheel, a guide wheel, and a belt mounted on said wheels to be operated by the driving wheel, of a platform supported in proximity to the guide wheel, two stripper heads having stems supported upon the platform, one of the stems being slightly elastic to hold the stripper head yieldingly to the remaining one of said heads, a spring having support on said platform for controlling the elasticity of said stem, and a carrier mounted on said belt to carry the willow to the 70 stripper heads.
- 35 7. In a willow bark remover, the combination with a driving sprocket wheel, a guide wheel, and a plurality of co-operating stripper devices supported adjacent to the 75 guide wheel, of a sprocket chain extending about said wheels to be driven by the driving sprocket wheel, a base clamp secured to the sprocket chain and having a pivot and, also, a pair of gripper jaws thereon, 80 one of the jaws being connected with the pivot, each jaw being provided with an arm, a supported spring engaging the arm of the pivoted jaw, and stationary guides to be engaged by the arms of said jaws 85 respectively to control the jaws.
- 40 8. In a willow bark remover, the combination with a driving wheel, a guide wheel, and stripping devices supported in proximity to the guide wheel, of a feed-plate 90 supported at an inclination with its lower end adjacent to the driving wheel and having a pair of guides thereon, a stop gate pivotally connected with the feed-plate and normally extending between the lower end 95 thereof and the driving wheel, a belt extending about said wheels to be operated by the driving wheel, and a carrying device mounted on said belt to be carried into engagement with the stop gate to move said 100 gate away from the lower end of said feed-plate.
- 45 9. In a willow bark remover, the combination with a driving wheel, a guide wheel, and stripping devices in proximity to the 105 guide wheel, of a feed-plate in proximity to the driving wheel and having a movable stop gate thereon, a belt extending about said wheels to be operated by the driving wheel, a carrying device mounted 110 on said belt to convey the willow from the feed-plate to the stripping devices, a cleaner for the stripping devices mounted on said belt and having a movable finger to operate on the devices, and a curved guide 115 supported in proximity to the driving wheel to be engaged by said finger to move the finger aside in passing said stop gate.
- 50 10. In a willow bark remover, the combination with a feed-guide, and a separate 120 stripping means, of a carrier belt mounted to operate between the feed-guide and the stripping means, a plurality of pairs of stationary guides, and gripper devices comprising a base clamp secured to the carrier 125 belt and having a jaw rigid thereon, the jaw being provided with an arm to be carried into contact with one of each of the pairs of stationary guides, a movable jaw pivotally connected with the base clamp 130

and provided with an operating arm to be carried into contact with the remaining one of each of the pairs of stationary guides, and a spring under compression between the arms of the jaws.

11. In a willow bark remover, the combination of a stationary stripper head, a movable stripper head, a wheel having guide arms and rotatably mounted on said movable head, a latch bolt mounted in said movable head and spring-pressed to engage and stop said wheel, a trigger mounted on said movable head and connected to the latch bolt, a carrier belt movably guided

to operate adjacent to said heads, a carrier 15 mounted on said belt, and a cleaner mounted on said belt and having a finger to be carried between said heads and toward one of said guide arms, the cleaner having also a trip device thereon to engage said trigger 20 and thereby retract the latch bolt from said wheel.

In testimony whereof I affix my signature in presence of two witnesses.

GEORGE WALTER.
